(Cl. D29—1)

FIGURE 1 is an elevational view of a Christmas ornament showing my new design, and

FIG. 2 is a side elevational view thereof, the border around the edges as seen in FIG. 1 having been omitted from this view for convenience of illustration.

The undisclosed opposite sides are similar in appearance to the sides shown in FIGS. 1 and 2. The dominant features of the design reside in the portions shown in solid lines, a conventional hook member being shown in broken lines at the top of the ornament.

I claim:

The ornamental design for a Christmas ornament, as shown and described.
